UNITED STATES PATENT OFFICE.

GILBERT RATHMAN, OF NEW YORK, N. Y.

SPEED-REDUCING GEARING.

1,232,717.

Specification of Letters Patent. Patented July 10, 1917.

Application filed January 13, 1917. Serial No. 142,218.

To all whom it may concern:

Be it known that I, GILBERT RATHMAN, a citizen of the United States, and a resident of the borough of Manhattan, city, county, and State of New York, have invented certain new and useful Improvements in Speed-Reducing Gearing, of which the following is a specification.

This invention relates to improvements in that type of speed-reducing gearing known as eccentric differential reduction gearing, in which an internally toothed gear affixed to the driven shaft, is driven by means of an annular rack held in constant mesh with the aforesaid gear and caused to gyrate within the same, this annular rack being held against rotation on its own axis and having a gyroscopic movement imparted to it by means of an eccentric affixed to the driving shaft, means being provided for preventing the annular rack and its eccentric-strap, to which it is rigidly attached, from rotating on their own axes.

The object of my invention is to provide an extremely simple and strong gear of the type set forth, so constructed that irregular or jerky motion of the annular driving rack is eliminated, and perfect meshing of the teeth of the rack with the teeth of the internal driven gear is insured, to the end that the driven shaft shall have a smooth, even, regular movement imparted thereto.

In the drawing, Figure 1 is a vertical longitudinal section;

Fig. 2 a vertical section on the line 2-2 of Fig. 1; and Fig. 4 a vertical section on the line 3-3 of Fig. 1, showing a perfect embodiment of my invention;

Figs. 3 and 5 are views similar to Fig. 4, showing modified embodiments of the invention.

Referring to the various parts by numerals, 10 designates the slow-speed or driven shaft carrying the internal gear 11, and 12 designates the high-speed driving shaft carrying the eccentric 13 and having its inner end journaled in a central recess 14 in the body of the internal gear, the object of thus supporting the inner end of the driving shaft on the driven shaft being to insure exact axial alinement of these shafts and thus at all times maintain the parts in their proper mechanical relation.

On the eccentric is mounted a strap 15, and rigidly affixed to this strap is the annu-

lar rack 16. Projecting radially from the eccentric strap is an anchoring or guiding member 17 whose outer end is bifurcated so as to embrace an eccentric 18 affixed to a stub shaft 19, this eccentric being an exact companion to the eccentric 13. The stub shaft is driven through the medium of a pair of gears 20 and 21; one being affixed to the driving shaft and the other to the stub shaft.

It will be observed that the rotation of the driving shaft through the medium of the eccentric 13 bodily rotates the annular rack or gear 16, keeping it always in mesh with the internal gear, and that this rack is prevented from axial rotation by means of the anchoring and guiding member 17, thus positively driving the internal gear at a slower speed than the driving shaft, the difference in speed being determined by the difference in diameter between the pitch line of the annular rack and the pitch line of the internal gear. The engaging of the anchoring member 17 with an eccentric which is an exact duplicate of the main eccentric 13, and the driving of this supplemental eccentric positively from the driving shaft, not only permit the necessary free radial movement of the anchoring member, but also bring about a positive lateral shifting of the anchoring end of the rack-carrying member in exact unison with the end thereof which is mounted on the main eccentric, thereby at all times maintaining the anchoring member in a radial position or in a position exactly parallel thereto. The especially unique feature in my device lies in the fact that I provide means for positively shifting the anchoring member by means driven from one of the shafts, so that all faulty operation due to the inexact meshing of the annular rack with the internal gear will be completely obviated, thus insuring an even and regular rotation of the internal gear and a smooth, continuous revolution of the slow-speed driven shaft.

It is obvious that my invention may be carried out by a variety of mechanisms, all of which come within the scope of my claims. In Fig. 3 I show the use of an intermediate idle gear 22 for connecting the two gears 20 and 21, whereby the gears 20 and 21 are driven in the same direction, the two eccentrics 13 and 18 being rearranged accordingly. In this form of the apparatus the outer end of the anchoring member is

formed into a strap closely embracing the eccentric in the same manner as the inner end of the anchoring member, whereby the anchoring member will not only be positively shifted laterally but also inwardly and outwardly. In Fig. 5 the same intermediate gear 22 is employed, but, instead of eccentrics for gyrating the annular rack, I provide the shafts 12 and 19 with a pair 10 of radial arms 23 and connect the same by means of a pivotal link 24, whereby the anchoring end of the anchoring member will be positively given a movement in exact unison with the inner end of the anchoring 15 member.

What I claim is:

1. In a gearing of the class set forth, a driven shaft, an internal gear fixed to said driven shaft, a driving shaft, a pinion fixed 20 on the driving shaft, a gyratory gear meshing with the internal gear, means fixed on the driving shaft whereby said gyratory gear is gyrated, a counter shaft, a pinion fixed on the counter shaft and meshing with 25 the pinion on the driving shaft, and means operated by the driving shaft through the medium of said pinions for holding the gyratory gear against axial rotation.

2. In a gearing of the class set forth, a 30 driven shaft, an internal gear fixed to said driven shaft, a driving shaft, a pinion fixed on the driving shaft, a gyratory gear meshing with said internal gear, means fixed on the driving shaft for gyrating the gyratory 35 gear, an anchoring member connected at one end with said gear-gyrating means, a counter shaft, a pinion fixed on the counter shaft and meshing with the pinion on the driving shaft, and means driven from the driving 40 shaft through said pinions operatively connected with the opposite end of said anchoring member for positively shifting and guiding said anchoring member to hold the gyratory gear against axial rotation.

3. In a gearing of the class set forth, a 45 driven shaft, an internal gear fixed to said

driven shaft, a driving shaft, an annular driving rack meshing with the internal gear, an eccentric carried by the driving shaft, a counter-shaft, a pinion fixed on said counter-shaft, a pinion fixed on the driving shaft and meshing with the pinion on the counter-shaft, a supplemental eccentric carried by the counter-shaft, and means operated by 50 said eccentrics for imparting a gyratory movement to the annular driving rack and for holding said rack against rotation on its axis.

4. In a gearing of the class set forth, a driven shaft, an internal gear fixed to said 55 driven shaft, an annular driving rack meshing with said internal gear, a driving shaft, an eccentric carried by the driving shaft, a strap mounted on said eccentric and rigidly affixed to the driving rack, an anchoring member connected to said strap, a supplemental eccentric engaging the anchoring member and having the same throw as the eccentric carried by the driving shaft, and means for positively rotating the supplemental eccentric through the medium of the 60 driving shaft.

5. In a gearing of the class set forth, a driven shaft, an internal gear fixed to said 65 driven shaft, an annular driving rack meshing with said internal gear, a driving shaft, an eccentric carried by the driving shaft, a strap mounted on said eccentric and rigidly affixed to the driving rack, an anchoring member connected to said strap, a supplemental eccentric engaging the anchoring member and having the same throw as the eccentric carried by the driving shaft, and means for positively rotating the supplemental eccentric through the medium of the 70 driving shaft, said driving shaft having one end journaled in and supported by the adjacent end of the driven shaft.

In testimony whereof I hereunto affix my signature.

GILBERT RATHMAN.
